HOLDER FOR TOOTHPASTE TUBES

Minor W. Johnson and James J. Lester, Nashville, Tenn., assignors, by direct and mesne assignments, of one-half to said Lester and one-half to A. L. Hanover

Refiled for abandoned application Serial No. 708,178, January 25, 1934. This application June 11, 1935, Serial No. 26,066

2 Claims. (Cl. 221—60)

This invention relates to improvements in holders for toothpaste tubes, having particular reference to that type of holder provided with rollers between which the tube is compressed for forcing the contents of the tube therefrom and this application is a refile of forfeited application, Serial No. 708,178, which was allowed May 3, 1934.

An object of the invention is to provide a holder of this character which can be economically and cheaply constructed, which can be readily secured to a wall or other suitable support and which will be practical and efficient in operation.

The invention together with its objects and advantages will be best understood from a study of the following description taken in connection with the accompanying drawings wherein:

Figure 1 is a front elevational view of the holder.

Figure 2 is a side elevational view thereof.

Figure 3 is an elevational view of the opposite side of the holder.

Figure 4 is a top plan view thereof.

Figures 5 and 6 are sectional views taken substantially on the lines 5—5 and 6—6 respectively of Figure 1.

Figure 7 is a perspective view of a roller shifting member.

Figure 8 is a perspective view of a spacer plate to be hereinafter more fully referred to.

Figure 9 is a plan view of the blank from which the holder is formed, and

Figure 10 is a perspective view of a tooth brush holder forming part of the invention.

Referring to the drawings by reference numerals it will be seen that 10 indicates generally a metallic or other suitable blank which is cut, shaped and dimensioned to provide a holder having a back plate or wall 11 and opposed sides 12 formed by folding the blank on the parallel fold lines 13. At the upper and lower ends of the back plate or wall 11 are provided apertured attaching flanges 14 whereby provision is made for securing the holder on the wall or other suitable support by suitable fastening elements 15.

Supported between the side members 12 are corrugated rollers 16, 17. Roller 16 has pintles journaled in suitable apertures 18 provided therefor in the sides 12 of the holder while the roller 17 has its pintles journaled in slots 19 provided on extensions 20 formed on the outer edges of the sides 12.

For turning the roller 16 in the proper direction there is provided on one end thereof a suitable handle 21 and for transmitting movement of

the roller 16 to the roller 17 there is provided on the end of the roller 16 opposite to the handle 21 a gear wheel 22 that is in mesh with a gear wheel 23 provided on a corresponding end of the roller 17. In this connection it will be noted that the teeth of the gear 23 are longer than the teeth of the gear 22 so as to preclude disengagement of the gears as a result of a spacing of the roller 17 relative to the roller 16.

The roller 17 is yieldably urged toward the roller 16 through the medium of plates 24 that are provided with apertures 25 through which extend the pintles of the roller 17. The plates 24 are provided with spaced parallel coextensive arms 26 that are provided at their free ends 15 with hooks 27. Engaged with the hooks 27 are one end of coil springs 28. The coil springs 28 have their free ends provided so as to engage suitable hooks 29 struck out from the rear wall or back plate 11. It will be apparent that the springs 28 will normally urge the plates 24 toward the back plate 11 of the holder and consequently corrugated roller 17 toward the roller 16 to engage between the rollers the paste tube 30 in a manner clearly suggested in Figure 5. In this connection it will be noted that corrugations on the rollers 16 and 17 so engage the tube 30 that when the handle 21 is turned in one direction for rotating the rollers 16, 17 in relatively opposite directions tube 30 will be drawn upwardly between the rollers in a manner to press the tube as suggested in Figure 5 for forcing the contents of the tube from the neck thereof.

The sides 12 of the holder are secured in fixed 35 spaced relation through the medium of a spacer plate 31 and the ends thereof are provided with suitable slots 32 through which are passed lips 33 which are subsequently flattened out in a manner to secure the ends of the plate 31 to 40 the sides 12 as suggested in Figures 1 and 4.

In actual practice, the holder is secured to a wall or other suitable support and the sealed end of the tube 30 is inserted upwardly between the rollers 16, 17 and is secured in position 45 therebetween by reason of the roller 17 under action of the springs 28 on the plates 24 being forced toward the roller 16. When it is desired to force some of the contents from the tube 30 the handle 21 is rotated in a clockwise direction causing the rollers 16, 17 to rotate in reverse directions relative to one another for drawing the tube 30 upwardly between the rollers to thereby compress the tube in a manner to force some of the contents of the tube through 55

the outlet neck of the tube on to the tooth brush or the like.

A suitable casing or pocket forming member 34 is also provided, and at the open side thereof 5 (which side is disposed against the rear plate 11 of the holder as shown in Figure 4) the lateral flanges or sides of the casing 34 are provided with laterally projecting lugs 35 that engage in notches 36 for securing the casing 34 in position on the holder and in a manner to accommodate the tooth brush or brushes 37 as shown in Figure 5. The notches 36, as shown in Figure 9, are provided in the upper edges of the sides 12 immediately adjacent to, and at one side of 10 the crease lines 13.

To prevent retrograde movement of the rollers 16, 17 the handle equipped end of the roller 16 is provided with a ratchet wheel 38 with which is engaged the end of a dog 39 pivotally mounted 20 on the adjacent side member 12 of the holder as shown in Figure 2. Yieldably engaging the end of the dog 39 with the ratchet wheel 38 there is provided a suitable spring 40 which is connected at one end to said side 12 and has 25 a free end engaging the dog 39 as also shown in said Figure 2.

Having thus described our invention, what we claim as new is:

1. A holder for toothpaste tubes comprising a

back plate having spaced parallel side members projecting therefrom, a pair of rollers journaled between said side members, one of said rollers mounted for lateral movement toward and away from the other of said rollers, plates engaging the pintles of said one roller, springs connecting said plates with the back plate of the holder in a manner to urge said one roller toward said other of said rollers for engaging and compressing between the rollers the tube, gearing connecting said rollers in a manner to cause the rollers to rotate in relatively opposite directions to cause the paste tube to move upwardly between the rollers, and means connected with said other of the rollers for rotating it. 15

2. A holder for toothpaste tubes comprising a supporting structure, a pair of rollers journaled in the supporting structure, one of said rollers mounted for lateral movement toward and away from the other of said rollers, plates engaging 20 one roller, springs connecting said plates with the supporting structure in a manner to urge said one roller toward said other of said rollers for engaging and compressing between the rollers the tubes, and means whereby the rollers may 25 be rotated in relatively opposite directions to cause the tube to move upwardly therebetween.

MINOR W. JOHNSON.
JAMES J. LESTER.
